UNITED STATES PATENT OFFICE.

GEORGE J. GINTERT, OF SHELLSBURG, IOWA.

GATE.

No. 904,862.

Specification of Letters Patent.

Patented Nov. 24, 1908.

Application filed August 13, 1907. Serial No. 388,372.

To all whom it may concern:

Be it known that I, GEORGE J. GINTERT, a citizen of the United States, residing at Shellisburg, in the county of Benton, and 5 State of Iowa, have invented a new and useful Improvement in a Gate, of which the following is a specification.

This invention relates to gates and more particularly to swing gates, the object being 10 to provide novel means for opening the gate so that it can be opened and closed from either side without getting out of a vehicle.

Another object of my invention is to provide a novel latch in connection with the 15 gate, so that it will be released before the gate starts to swing.

Another object of my invention is to provide means for locking the gate in an opened position on either side.

20 In the drawing I have shown a perspective view of my gate, in which A and B indicate a pair of posts arranged on each side of a road, to which the fence is connected. The post A being provided with pintle irons 25 C on which are mounted eyes D carried by one of the vertical bars of a gate-frame E which may be of any desirable construction, and it will be seen that the gate is so mounted that it can be swung in either direction, as will be hereinafter fully described.

A flat spring F is secured on the outer face of the end of the gate forming a latch which is provided with a lug F' adapted to fit in 35 a catch G secured on the face of the post B. The spring is held in position by a rod F² which slides through an opening formed in the gate. The upper end of the latch has apertures, in which are secured the ends of 40 cables H and I which pass over pulleys J', K' carried by arms J and K extending out from the top bar of the gate and over pulleys L' M' carried by arms L and M se-

cured on posts N and O arranged on each side of the post A, and up over pulleys 45 P', Q' carried by the ends of bars P and Q secured under posts N and O, the lower ends of the bars being secured to the post A. The ends of the cables are provided with knots so that they can be readily grasped by the 50 hand and it will be seen that as either cable is grasped, the gate will swing in that direction the pull being first on the latch so as to throw it out of engagement with the catch, and as the cables are pulled further 55 down, the gate will swing open and the latch will engage a catch R secured on the post O which will securely lock the gate in an opened position. After the team has passed through the gate, the cable on the other side 60 by being pulled will release the catch and allow the gate to be pulled close. The catch S is secured to the post N, so that when the vehicle passes through the other way and the gate is swung open, it will be locked in 65 that position.

From the foregoing description it will be readily seen that I have provided a gate which is very simple and cheap in construction and one which is composed of a very 70 few parts, so as to prevent the gate from getting out of order.

What I claim is:—

The combination with a swinging gate, of a spring latch carried by the gate, arms extending outwardly from the gate carrying pulleys, posts arranged to each side of said gate carrying pulleys, and cables passing over the pulleys of the posts and the pulleys of the gate having their ends connected to 80 the spring latch, for the purpose described.

GEORGE J. GINTERT.
